UNITED STATES PATENT OFFICE.

CHARLES R. FARGO, OF CHICAGO, ILLINOIS, ASSIGNOR TO WILSON-JONES LOOSE LEAF COMPANY, OF CHICAGO, ILLINOIS, A CORPORATION OF ILLINOIS.

TRAY LOOSE-LEAF BINDER.

1,247,945.

Specification of Letters Patent. Patented Nov. 27, 1917.

Application filed April 20, 1916. Serial No. 92,461.

To all whom it may concern:

Be it known that I, CHARLES R. FARGO, a citizen of the United States, and a resident of the city of Chicago, in the county of Cook and State of Illinois, have invented certain new and useful Improvements in Tray Loose-Leaf Binders; and I do hereby declare that the following is a full, clear, and exact description of the same, reference being had to the accompanying drawings, and to the numerals of reference marked thereon, which form a part of this specification.

This invention relates to an improved type of loose leaf binder of the so-called "tray" type which has come into wide use in what are known in the trade as "machine book-keeping systems." The binder is so constructed as to be used with a particular kind of stand or support to facilitate removal and insertion, as well as shifting of the pages or leaves and in a manner such that the same are all properly aligned so that the binder may be readily closed and locked up when it is desired to remove the same from the stand.

It is an object therefore of this invention to construct a tray binder adapted for use on a supporting stand so as to be opened and separated with the leaves or pages loosely contained in the cover trays thereof, and with means for properly registering the leaves when the same are inserted or replaced after removal, in the binder cover trays.

It is also an object of this invention to construct a tray binder for use in a machine book-keeping system embracing covers and back or end plates constructed to afford trays when the binder is opened upon a stand provided therefor, and with said covers further equipped with means for insuring proper registration of the leaves when they are placed upon the tray members.

It is also an object of this invention to construct a separable loose leaf binder wherein the covers are constructed to form tray members when detached from one another, and with said covers provided with means to receive the impaling posts of the binder when detached from the usual position, in a new position whereby the same act as an alining or registering means for the loose pages or leaves in the trays.

It is furthermore an important object of this invention to provide a tray binder consisting of separable covers having back plates hingedly connected thereto with the back plates adapted to be interlocked with one another to lock said covers one to another with the pages held engaged therebetween and when in unlocked position adapted to be disposed upon a stand provided for the purpose to afford trays with means for registering the leaves or pages as they are removed or interchanged or inserted into place on the respective trays.

It is finally an object of this invention to construct an improved type of tray binder embodying a number of novel features of operation and construction, and further provided with detachable means for insuring proper registration of the leaves or sheets as they are placed into the trays when the binder is opened and separated to form tray sections.

The invention (in a preferred form) is illustrated in the drawings and hereinafter more fully described.

In the drawings:

Figure 1 is a front view of a binder in closed position embodying the principles of my invention mounted upon a stand provided for the purpose.

Fig. 2 is a view looking down on the binder upon the stand at an angle and with the binder unlocked and in open separated position.

Fig. 3 is a view similar to Fig. 2, illustrating the leaves disposed in the trays formed by both the covers of the binder with the registering means in place on each thereof.

Fig. 4 is a detail section taken on line 4-4 of Fig. 1, with parts omitted.

Fig. 5 is a fragmentary view with parts broken away at the hinged end of one of the tray covers of the binder.

Fig. 6 is a top plan view of the binder in open position, with the binder posts transferred to registering position.

Fig. 7 is a fragmentary detail view with parts in section, illustrating the back plates of the respective covers of the binder moved out of register with one another.

Fig. 8 is a fragmentary detail section taken on line 8-8 of Fig. 6.

Fig. 9 is a fragmentary plan view with parts broken away to show the construction, of a portion of the covers of the binder at the points provided for reception of the 5 alining or registration pins.

Fig. 10 is a fragmentary detail section taken on line 10—10 of Fig. 9.

As shown in the drawings:

The frame or stand on which the tray 10 binder is used consists of a pair of wooden strips 1, rigidly connected together by transverse metallic bars 2, and secured to each of the strips 1, and extending across the upper surface of each thereof are metal 15 bars 3, bent to a W-shape such as shown clearly in Fig. 1, so that each respective half of the pair of W-bars 3, is adapted to receive thereon a tray member of the binder. The binder itself consists of covers denoted 20 as a whole by the reference numeral 4, and at the inner ends thereof angle shaped back plates are secured, as shown in detail in Figs. 4, 7, and 8, the angle plate of one of said covers denoted by the reference numeral 25 5, and the other denoted by the reference numeral 6.

As clearly shown in Figs. 7 and 8, the angled back plate 5, is disposed over the inner surface of the angled back plate 6, and 30 means are provided for locking the same in registration with one another. For this purpose, each of said back plates is provided with recesses 7 and 8, respectively, at each end thereof, the recess 7, of the plate 35 5, adapted to register with the recess 8, of the plate 6, when the plates 5 and 6, are disposed properly one over the other. Pivoted on the upper surface of the plate 5, is a small flat crank or lever 9, with a pin 10, 40 secured in the end thereof adapted to be engaged with the recesses 7 and 8, when the same are registered with one another. Also secured on said crank or lever 9, is a resilient spring member 11, normally sprung 45 downwardly through a recess provided in said lever and provided with a detent 12, adapted to engage with an indent 13, provided to receive the same in the top surface of the plate 5, to retain said lever 9, in its 50 locked position.

A projecting pin 14, is also provided at each end of the back plate 6, and when said plate 5, is moved into proper registration thereover, the same fit into corner recesses 55 15, provided in said plate 5, to assist further in holding the plates properly registered and associated with one another. The hinge connection between the respective covers 4, and the angled back plates 5 and 6, is denoted as a whole by the reference numeral 60 16.

The cover members of the binder are constructed as usual of superposed layers of binder board or other suitable material, as 65 shown in the sectional view in Fig. 10, and

mounted in a recessed portion of said covers near the top edge of each thereof is a recessed pin receiving block comprising sheet metal plates 17 and 18, respectively, riveted to one another, and having inserted 70 therebetween at the middle portion thereof a metal block 19. Thus a strong retaining means to receive one of the binder impaling posts 20, inserted in the aperture therein, is provided, with the metallic wings on each 75 side of said block extending for a relatively great distance into and between the layers of material of the built-up cover members to afford a very substantial construction.

The leaves or pages used in the binder 80 or ledger are denoted by the reference numeral 21, and for the purpose of retaining the same within the ledger when the covers thereof are locked together by the respective levers 9, the pages are apertured to receive 85 the binding posts 20, which engage at their ends in suitable recesses provided therefor through the angled portions of the respective back plates 5 and 6.

The operation is as follows:

The binder when closed and locked is substantially similar in all respects to the usual type of loose leaf ledger, that is, the pages 21, are held between the covers of the binder by binding posts 20. When it is desired, 95 however, to shift or change the pages or leaves within the binder such as when "posting the books" the binder may be conveniently laid upon the stand provided therefor, the W-shaped supporting bars 3, 100 affording a convenient means for supporting each of the covers of the binder individually and yet conveniently adjacent one another in an open book position such as shown in Figs. 2 and 3. The covers of the 105 binder when unlatched and placed in such position each form substantially a tray within which the leaves of the binder are laid. Inasmuch as the removal of the impaling or binding posts 20 of the binder 110 generally necessitates loss of time and inconvenience in replacing the same, due to the fact that it is difficult to properly register the pages of the binder for insertion of the binding posts through the apertures 115 therein, the binding posts 20, are utilized to effect an exact registration and alinement of the leaves while they are laid loosely upon the tray members. The two binding posts, which are necessarily removed from engagement with both of the cover members of the binder when the same is opened up so as to permit an easy interchange and shifting of the leaves, are utilized, as mentioned, as registering means, 120 by inserting them into apertured plates 19, concealed within the material of which the covers are made near the upper edges thereof. Thus pages or leaves placed upon the cover tray members are limited from move- 125 130

ment at two edges and therefore registration of the respective pages is assured, so that when the binder is again locked up the apertures in the leaves will be in register 5 with one another and with the apertures provided for the ends of the binder posts in the binder plates, so that the binding posts may be easily inserted into place and the covers of the binder locked together. 10 The locking means by which the covers of the binder are locked together is simple, and as clearly shown in Fig. 7, merely consist of pivot levers 9, and a stationary locking pin 14, at each end of the device. 15 The construction of the binder according to the principles of my invention permits the use of leaves having round apertures punched in one of the side margins thereof, and this feature provides a more convenient 20 sheet for handling, particularly in inserting and removing the same in or from a typewriter, than the usual type of sheet which has V-notches in its lower margin, and consequently oftentimes becomes damaged when so handled. Further, a binder which permits use of sheets having side 25 margin apertures for engagement, is far more easy to handle, inasmuch as the type using the bottom engaging sheet must be turned completely around for reference to 30 the back surface of the sheet.

I am aware that various details of construction may be varied through a wide range and I purpose claiming broadly the 35 idea of utilizing the detached impaling or binding posts of a binder or ledger in another position or relation with respect thereto for the purpose of effecting proper registration of the leaves of the binder when 40 laid loosely in the cover members of the binder, and I therefore do not purpose limiting the patent granted otherwise than necessitated by the prior art.

I claim as my invention:

45 1. In a construction of the class described, a tray binder for use upon a stand comprising cover members, back plates hingedly connected thereto and together with the cover members affording a tray, binding posts to 50 retain pages engaged between the covers of said binder, and auxiliary means on said covers adapted to receive said binding posts engaged therewith when detached from normal position of engagement therewith and 55 with said pages to insure proper registration of the leaves with one another when laid in the trays formed by the cover members when in open separated relation.

60 2. In a construction of the class described, separable cover tray members, binding posts adapted to retain leaves engaged therebetween when said cover tray members are locked to one another, and means on said cover members to receive said binding posts engaged therewith to insure proper regis-

tration of the leaves when laid loosely upon the cover tray members.

3. In a device of the class described, cover tray members, means adapted to interlock the same with one another, means detachably engaged with said cover members adapted to retain leaves therebetween, and means adapted to receive said second mentioned means engaged therewith when said cover tray members are laid in separated 75 relation to insure proper registration of the leaves laid upon the cover tray members.

4. In a construction of the class described, a pair of cover tray members, means locking the same one to another, each of said members provided with recesses, impaling posts adapted to be engaged therewith to hold leaves engaged between said cover members, and recessed means provided in each of said cover members adapted to receive impaling 85 posts engaged therewith when removed out of engagement at normal position and with said leaves to insure proper registration of the leaves when the same are laid upon the separated cover members. 90

5. In a tray binder for use with a stand, separable cover tray members, binding posts detachably engaged therewith adapted to retain leaves engaged therebetween, and means associated with each of said cover members 95 adapted to receive said posts engaged therewith to insure proper registration of the leaves of the binder when laid loosely upon the separated cover tray members.

6. In a construction of the class described 100 for machine book-keeping, a binder comprising separable cover members releasably connected to one another, back plates hingedly connected thereto, a stand upon which said cover members are adapted to be disposed when released from one another whereby the hinged back plates are supported in certain relation with the cover members to afford trays, binding posts for retaining leaves between the cover members 110 when the same are in locked relation with one another, and means disposed in the cover members to receive said binding posts to insure proper registration of said leaves upon the trays when the cover members are 115 separated one from another.

7. In a device of the class described, a binder, means retaining leaves therein, and means adapted to receive said first mentioned means engaged therewith when detached from retaining position in said binder to insure proper registration of the leaves upon the separated members of the binder. 120

8. A binder of the class described 125 comprising covers, a separable back plate associated with each thereof, binding posts engaged in said back plates to hold leaves between the covers, and means associated with said covers adapted to receive said binding 130

- posts engaged therewith when the binder is opened and the covers and back plates separated.
9. A tray binder comprising separable back plates, cover members hinged thereto, said back plates provided with recesses to receive the binding posts engaged therewith to hold the pages between the covers, and means associated with said covers to receive the binding posts engaged therewith for registration of the leaves laid upon the covers after detachment of the binding posts from said back plates.
10. A binder comprising separable sections adapted when separated to form leaf trays, and means for alining the leaves on the trays.
11. A loose leaf binder comprising sections adapted when opened up to form trays for loosely supporting leaves and means alining the leaves on the trays to permit quick assembling and closing of the binder.
12. A loose leaf binder comprising tray sections adapted to be separated to provide trays for holding loose leaves and to be put together to form a loose leaf binder, and means adapted to aline the leaves when the sections are separated and adapted to have the leaves impaled thereon when the sections are assembled.
13. A loose leaf binder comprising two sections detachably connected together, each adapted to act as a tray for loose leaves when detached from the other.
14. A loose leaf binder comprising two sections detachably connected together, each adapted to act as a tray for loose leaves
- when detached from the other, and means for alining the leaves on either tray when the sections are detached.
15. In a device of the class described, loose leaf binder sections adapted to be detached one from the other, and posts for receiving the loose leaves thereon and removable from the sections to permit free shifting of the leaves from one tray to the other.
16. In a tray binder, cover sections separable one from the other and adapted when separated to form tray sections, and binding posts adapted to retain the leaves in the binder when closed and said covers being adapted to hold the binding posts in position to aline the leaves when adjusted from one tray to the other when the binder is open.
17. In a binder of the class described binder sections, impaling and alining posts detachably secured to the sections, and independent means secured to said sections for detachably securing the posts to the binder sections in different positions.
18. In a binder a plurality of cover sections, each having apertures therein in different places and binding posts adapted to be detached from one set of apertures and inserted in the other apertures.
- In testimony whereof I have hereunto subscribed my name in the presence of two subscribing witnesses.
